WILLIAM RAY LAKEY, OF DENTON, TEXAS.

MILLING-MACHINE.

1,085,922.

Specification of Letters Patent.

Patented Feb. 3, 1914.

Original application filed July 23, 1912, Serial No. 711,145. Divided and this application filed April 12, 1913. Serial No. 760,680.

To all whom it may concern:

Be it known that I, WILLIAM R. LAKEY, a citizen of the United States, residing at Denton, in the county of Denton and State 5 of Texas, have invented a new and useful Milling-Machine, of which the following is a specification.

This invention has reference to improvements in milling machines, and its object is 10 to provide a machine for the thorough removal of dirt and other substances that should not follow the stock, and to carry the removed material to a dust collector for further treatment.

15 In accordance with the present invention the direction of travel of the stock is broken numerous times while the fall of stock from one direction changing means to the next is short, thereby admitting of relatively 20 strong air currents without liability of carrying away any parts of the falling stock except those which it is desirable should be extracted by such air currents. In the present machine the air currents traverse the 25 falling stock during each period of fall, while the parts are so dimensioned as to prevent any change in the action of the air currents on the dropping stock at different parts of the apparatus, so that there is no 30 liability of uneven action of the air currents and consequent escape of some portions of the removable parts of the stock on being carried by such moving stock toward the 35 action of the air currents.

40 The present invention also provides a means which will cool and partially dry the stock thereby materially aiding in the subsequent grinding and bolting, and thereby greatly improving the quality of the product and also increasing the yield and profits.

The invention will be best understood from a consideration of the following detailed description, taken in connection with the accompanying drawings forming a part 45 of this specification, with the further understanding that while the drawings show a practical form of the invention the latter is not confined to any strict conformity with the showing of the drawings but may be changed and modified so long as such 50 changes and modifications mark no material departure from the salient features of the invention.

In the drawings:—Figure 1 is an elevation of the machine embodying the present

invention. Fig. 2 is a section on the line 2—2 of Fig. 1 with some distant parts also shown in section.

Referring to the drawings there is shown a casing 1 having an inlet duct 2 discharging 50 into a hopper 3 at the lower end of which there is located a feed roller 4 and a gate 5, the latter being controlled by an adjustable weight 6 so that stock may be evenly spread and the degree of feed controlled by the 55 adjustment of the weight 6, the gate 5 being substantially pendent and the weight being carried by an arm 7 fast to and outstanding from the gate in a direction away from the feed roller. The gate is attached to the 60 hopper by a hinge 8 to permit its yield under the action of the grain and the movement of the feed roller 4. The arbor of the feed roller extends through the casing to the exterior thereof and may there carry a pulley 65 9 by means of which power may be applied to rotate the feed roller in the proper direction.

Beneath the hopper 3 the casing 1 is 70 formed with a slanting bottom member 10 80 leading toward one face 11 of the casing, which face may be termed the front face, and this slanting bottom leads to and discharges into an outlet 12.

Adjacent to and above the slanting bottom 85 10 there is a series of superposed slanting baffles 13, each higher one being in the main back of the next lower one with respect to the front 11, but with its lower edge 90 extending a short distance in front of the vertical plane of the upper edge of the next lower baffle. Each higher baffle is spaced from the slanting bottom 10 by a greater distance than the next lower baffle, so that the distance of the baffles from the slanting bottom 95 11 increases in ascending order. Moreover each higher baffle is vertically spaced from the upper edge of the next lower baffle so that a stream of material leaving the feed roller 4 will drop upon the upper portion of the top 100 surface of the first baffle and sliding down this baffle will fall therefrom through an intervening air space upon the second baffle near the upper end thereof, and so on throughout the series.

105 The front 11 is provided with an opening 14 traversed by a number of superposed inclined spaced slats 15 so that air may enter through the opening 14 in numerous streams. The casing is also provided with a window 110

- 16 by means of which the interior of the casing may be viewed from time to time as may be necessary. Communicating with the interior of the casing above the inclined or 5 slanting bottom 10 is a suction pipe 17 provided with a regulating valve 18.
- If it be assumed that the stock is entering the hopper 3 through the conduit 2 and air is being withdrawn through the suction 10 pipe 17 and, furthermore, that the feed roller 4 is rotating counterclockwise as viewed in Fig. 2, a thin wide stream of stock is fed past the gate 5 and gravitates upon the uppermost baffle 13 and is subjected in 15 its fall to an air stream traversing a space between the roller 4 and said baffle. The stream of material falls from each higher baffle on to the next lower baffle and from the lowermost baffle on to the slanting bottom 20 10 or directly into the escape conduit 12. During each point of free falling of the material from baffle to baffle the material or stock is traversed by an air stream coming from the front of the machine toward 25 the inclined bottom 10 and finally leaving the casing through the exhaust conduit 17. With the arrangement shown the action of the air stream is substantially the same at every point where the stock freely falls.
- 30 Moreover the extent of fall of the stock is in each instance comparatively short, so that strong air streams may be employed which will remove all material that it is desired should be removed from the stock, while not 35 carrying any part of the stock which it is desirable should not be removed. Even if the air streams be strong enough to cause some of the heavier portions which it is desirable should not be removed to travel toward the air suction pipe or trunk, the greater 40 weight of the heavier particles will soon release them from the influence of the air stream and they will fall upon the inclined bottom 10 and gravitate to the escape pipe or duct 12, wherefore the liability of loss of 45 material is practically eliminated even though the air streams be much stronger than heretofore employed in machines of this character. It is advantageous to employ strong air streams since the cleansing 50 is then much more effective than with air streams of less force, but in prior devices of the character of the present invention no attempt has been made to render the several 55 air streams practically uniform so far as their effect upon the stock is concerned and also to distribute these streams throughout the whole range of movement of the stock through the apparatus.
- 60 This application is a division of application No. 711,145, filed by me on July 23, 1912, for improvements in milling machines.

What is claimed is:—

1. In a machine for the purpose described, 65 a casing provided with a forwardly slant-

ing bottom member, a slanting series of superposed, slanting imperforate baffles in front of and above the bottom member, said baffles all slanting in the same direction, and each higher baffle having its lower edge in front of the vertical plane of and spaced above the upper edge of the next lower baffle, means for delivering material on to the uppermost of the series of baffles, air outlet means to the rear of and above the series of baffles, and air inlet means on the side of the series of baffles remote from the slanting bottom and positioned with respect to said baffles to direct air through the spaces between the baffles in traversing relation to streams of material falling from each baffle to the next lower one in order, the air inlet means being located opposite the lower baffles and below the higher baffles.

2. In a machine for the purpose described, a casing, a slanting series of superposed slanting imperforate baffles therein, all slanting toward the front of the casing, with each baffle in spaced relation to the next lower baffle to deliver on the upper end thereof, means for the withdrawal of air from the casing at a point higher than and to the rear of the baffles, and a forwardly slanting bottom member underriding the series of baffles, the casing being provided with openings in front of the series of baffles in position to direct air to and through the series of baffles toward the rear of the casing.

3. In a machine for the purpose described, a casing provided with a forwardly slanting bottom member, a series of superposed slanting baffles in front of and directly above the bottom member and all slanting in the same direction, the baffles increasing in distance from the slanting bottom in ascending order, means for delivering material upon the uppermost of the series of baffles, means for withdrawing air from a high point at the rear of the casing, and air inlet means at the front of the casing near the bottom portion of the series of baffles.

4. In a machine for the purpose described, a casing provided with a forwardly slanting bottom member, a rearwardly slanting series of superposed slanting baffles in front of and directly above the bottom member and all slanting forwardly and increasing in distance from the slanting bottom in ascending order, means for delivering material on to the uppermost baffle of the series, means for exhausting air from a high point in the casing to the rear of the series of baffles, and means for delivering material thereonto, said casing being provided at the front of the baffles with an opening and a series of superposed slats slanting downwardly with relation to the baffles, said opening being located opposite the lower

end of the series of baffles and below the upper end of said series.

5. In a machine for the purpose described, a casing provided with an upright front member having an opening therethrough near the lower end, a series of downwardly slanting slats lodged in the opening, an inclined bottom in the casing slanting downwardly toward the front thereof, and at the 10 lower end defining an outlet between the bottom member and the front of the casing, an exhaust duct at the top rear portion of the casing, means at a high point for introducing material into the casing, and a 15 rearwardly slanting series of superposed slanting imperforate baffles all directly

above the bottom member with each higher baffle having its lower edge in front of the vertical plane of and spaced above the upper edge of the next lower baffle and with the 20 uppermost baffle in position to receive material from the introducing means, the baffles of the series increasing in distance from the slanting bottom in ascending order.

In testimony, that I claim the foregoing 25 as my own, I have hereto affixed my signature in the presence of two witnesses.

WILLIAM RAY LAKEY.
